United States Patent Office

Des. 207,903
Patented June 13, 1967

207,903

HEAD REST

Earl H. Belk, 931 Long Beach Blvd.,
Long Beach, Calif. 90813

Filed Jan. 18, 1966, Ser. No. 661

Term of patent 14 years

(Cl. D15—8)

FIG.1

FIG.6

FIG. 1 is a perspective view of a head rest showing my new design;

FIG. 2 is a left side elevational view thereof, the right side elevational view thereof being a mirror image and omitted for brevity;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for a head rest, substantially as shown and described.
